UNITED STATES PATENT OFFICE

CLIFTON W. ARNOLD, OF HOUSTON, TEXAS

DISPLAY DEVICE

Application filed January 28, 1927. Serial No. 164,240.

This invention relates to new and useful improvements in a display device.

One object of the invention is to provide a device of the character described, specially designed for the purpose of displaying advertisements and the like and is of such construction that it may be readily mounted on a vehicle so as to be readily portable; however, the device may be mounted on a stationary support if desired.

A further feature of the invention is to provide an apparatus of the character described, which includes a plurality of display members with a display space on each side carrying advertisements and the like and a mechanism whereby the said members may be revolved around a common center as well as rotated on their axes so that the advertising matter on each side of each member will be displayed.

With the above and other objects in view the invention has particular relation to certain novel features of construction, operation and arrangement of parts, an example of which is given in this specification and illustrated in the accompanying drawings, wherein:

Figure 1 shows a side elevation of the device mounted on a motor vehicle and shown partly broken away.

Figure 2 is a vertical sectional view thereof taken on the line 2—2 of Figure 1.

Figure 3 is a fragmentary vertical sectional view taken on the line 3—3, of Figure 2.

Figure 4 is a vertical sectional view taken on the line 4—4 of Figure 1.

Figure 5 shows a vertical sectional view taken on the line 5—5 of Figure 1, and

Figure 6 shows a vertical sectional view taken on the line 6—6 of Figure 1.

Referring now more particularly to the drawings wherein like numerals of reference designate similar parts in each of the figures the numeral 1 designates the motor vehicle as a whole on which the device may be mounted. Upstanding from the vehicle body are the front and rear supporting members 2 and 3 which may be formed of sheet metal, if desired, or other suitable material and which support the top or cover 4. There is a longi-

tudinal shaft 5 rotatably mounted in suitable bearings in the respective supports 2 and 3 and fixed on the forward end of the shaft adjacent and in front of the front support 2 there is a ratchet wheel 6. The device is equipped with a suitable electric motor 7 which is wired in circuit with a storage battery 8, the wiring including a switch 9 for opening and closing the circuit. Wired into said circuit there is a clock having the usual time switch through which the motor is intermittently connected with and disconnected from the source of electrical energy so that the motor will run intermittently. The time switch mechanism referred to is of conventional construction and it has not been thought necessary to illustrate and describe the same in detail. The shaft of the motor 7 has a worm gear 11 fixed thereon in mesh with a corresponding gear 12 which is fixed on a suitable shaft 13, mounted in transversely aligned bearings 14, 14, carried by the vehicle body. One end of the shaft 13 has the crank arm 15 fixed thereon to the outer or free end of which one end of the pawl 16 is pivoted. The free end of the pawl is held in engagement with the ratchet wheel 6 by means of a pull-spring 17 one end of which is connected to said pawl and the other end of which is attached to the adjacent support 2. As the shaft 13 rotates the pawl will oscillate and will successively engage the teeth of the ratchet wheel 6 and impart a partial rotation thereto and to the shaft 5, successively. Fixed on said shaft 5 and spaced apart from the front and rear discs 18, 19. Between these discs there are a plurality of rotatable plate-like sign boards 20 whose opposite sides carry spaces for signs, advertisements and the like. The respective ends of the plates 20 are provided with front and rear end pintles 21, 22, respectively, which rotate in marginal bearings in the respective discs 18 and 19, said shaft 5 and discs 18 and 19 forming a supporting frame. The pintles 21 are extended forwardly and have the discs 23 fixed thereon and in front of said discs have the spur pinions 24 fixed thereon. The discs 23 have the oppositely disposed marginal notches 25 and fastened to

95

100

the forward side of the disc 18 are the spring dogs 26 whose free ends 27 are forwardly turned and extend forwardly beyond the corresponding discs 23. These forwardly turned ends 27 are provided to engage in a notch in the corresponding discs 23, to normally hold said disc against turning.

Fixed to the rear side of the support 2 are the upper and lower spur gears 28, 28, and carried by the rear side of said support 2 and disposed diagonally across the path of the overturned ends 27 of the dogs 26 are the upper and lower release bars 29, 29. As the shaft 5 rotates the display plates 20 will revolve with the discs 18 and 19, which are fixed on said shaft 5. The overturned ends 27 of the dogs 26 will successively engage the release bars 29 and be thereby lifted from their notches 25 and thereupon the corresponding spur gear 24 will engage the adjacent gear 28 and cause a partial rotation of the corresponding plate 20, the gear ratio being such that said plate will be given a one-half turn. As the overturned ends 27 pass the release bars 29 they will drop down into position to engage in the other notch 25 of the corresponding disc 23 so as to hold the corresponding plate 20 against further rotation until again released. Inasmuch as there are two of the gears 28 oppositely arranged each member 20 will be given one rotation with each revolution about the shaft 5 so that signs or advertisements carried by each side of each member will be successively displayed.

The operative mechanism is enclosed, and concealed from view by suitable front and rear side hoods as 30, 31.

The display boards 20 may be lighted at night by the electric lights 32 and are connected into the light circuit of the motor vehicle.

What I claim is:—

1. A display device including a support, a rotatable frame mounted on said support, a display member rotatably mounted in the frame and revolvable about the axis of the frame, a releasable dog carried by the frame and normally locking the display member against rotation on its axis, means carried by the support arranged to successively release said dog, as the frame rotates, to permit the display member to rotate on its axis, and operative connections carried by the support and display member respectively effective to impart partial rotations to the display member when said locking dog is released.

2. A display device including a rotatable frame, supporting means in which the frame is mounted, a display board rotatably mounted in the frame, interlocking means carried by the display board and the frame normally locking the display board against rotation on its axis, means for successively releasing said interlocking means to permit the display

board to rotate on its axis, and gearing carried by the supporting means and displaying board through which the display board may be rotated on its axis, when so released.

3. A display device including a supporting means, a frame rotatable therein, display members rotatable about their respective axes in the frame and revolvable about the axis of the frame as the frame rotates, means for imparting successive partial rotations to the frame, intermeshing gearing carried by the supporting means and each display member respectively and operative to impart partial rotations to said display members, respectively, as the frame rotates, releasable interlocking means carried by the frame and by the respective display members normally holding said display members against rotation on their respective axes, and means for successively releasing said interlocking means to permit said respective display members to be rotated about their corresponding axes as they revolve about the axis of the frame.

In testimony whereof I have signed my name to this specification.

CLIFTON W. ARNOLD.
